UNITED STATES PATENT OFFICE.

FREDERICK SNYDER, OF LANCASTER, PENNSYLVANIA.

LETTER-BOX ALARM.

SPECIFICATION forming part of Letters Patent No. 402,282, dated April 30, 1889.

Application filed October 2, 1888. Serial No. 287,029. (No model.)

To all whom it may concern:

Be it known that I, FREDERICK SNYDER, a citizen of the United States, residing at Lancaster, in the county of Lancaster and State 5 of Pennsylvania, have invented certain new and useful Improvements in Letter-Box Alarms; and I do hereby declare the following to be a full, clear, and exact description of the invention, such as will enable others 10 skilled in the art to which it appertains to make and use the same.

This invention relates to alarm mechanism for letter-boxes, whereby the uncovering of the opening through which the letters are 15 dropped is announced audibly.

The object of said invention is to make such mechanism secure, as well as simple and strong.

To this end the said invention consists in 20 the construction and combination of parts, hereinafter particularly set forth and claimed.

In the accompanying drawings, Figure 1 represents a vertical section from front to rear through the front of the letter-box and the alarm mechanism. Fig. 2 represents a 25 rear elevation of the alarm mechanism and the plate to which it is attached. Figs. 3, 4, and 5 represent, respectively, in detail the hammer, the hammer-carrier, and the trip-bar. Figs. 6 and 7 represent front and rear 30 views of the front plate and the slide which covers and uncovers the opening therein.

A designates the front of the box, having a front plate, B, secured on its face. In said plate is an opening, b, for receiving letters, which communicates with the usual downwardly-inclined passage, a, leading to the interior of said box. The back of said front plate is recessed, as shown at b', to afford 35 space for a slide-plate, C, which may be moved upward in the guideway left between said plate and the front of the box. This upward motion uncovers the opening b and passage a, and is effected by means of a handle 40 or finger-piece, C', extending forward from said slide through an elongated opening or vertical slot, b', in plate B. This slot communicates with opening b, and is long enough 45 to allow the lifting motion described. In 50 breadth the shank c of finger-piece C' fits said slot b', so as to move easily up and down

therein; but said handle is constructed with a broader front part or plate, c', which overlaps the sides and upper edge of said slot, affording an additional guide for slide-plate C, 55 and hiding the opening through front plate, B, made by said slot, so that there can be no access to the interior of the box through this slot.

Slide-plate C is provided on its rear face 60 with a rigid inwardly-extending arm, C², which passes through a vertical slot, A', in the front A of the letter-box, and also through a corresponding slot, d, of a plate, D, secured to the rear side of said box-front. The inner end of 65 said arm C² also enters a slot, e, similarly arranged to d, but shorter, in a longitudinally-movable trip-bar, E. This trip-bar is guided partly by an overlapping bent lug, d', of plate D and partly by the sides of an opening, d², through which said bar extends in a circumferential raised flange or rim, D', of 70 said plate. The lower end of said bar is enlarged and provided with a triangular opening, E², which receives a stud, D², on the plate 75 D, and is partly overlapped by another bent lug, d³, which serves to guide said lower end of said trip-bar and hold it in position to work. On one side this lower part is provided with a rigid nose, E³, which engages 80 with a nose, f, of a hammer-carriage, F. A spring, G, wound on a stud, G', of said plate bears at one end against a stud, g, on said bar and at the other end against a stud, g', 85 on said hammer-carriage and operates to hold 90 said noses together. Said hammer-carriage is pivoted at the middle on a stud, F, of plate D, and has at its lower end a tongue, f', extending under bent lug d³, so that said nose f may be guided and held in position thereby. On the other end of said hammer-carriage a hammer, H, is pivoted, the tail of 95 said hammer and the corresponding part of said hammer-carriage being curve-grooved to form a small chamber, h, which receives a spring, h', acting against a lip, h², of said hammer to retract the latter from the gong I. This gong normally covers the operative mechanism aforesaid.

When the slide-plate C is raised to uncover 100 opening b and passage a, the arm C' moves upward till it reaches the upper end of slot e,

when it lifts trip-bar E. The engagement of the noses E³ and f causes the hammer-carriage F to turn on its pivot against the resistance of spring G until the former nose slips 5 by the latter one. The spring G then turns the hammer-carriage suddenly in the opposite direction; but said carriage is checked by the contact of fixed lug d³ with tongue f' before the hammer strikes the gong. The momentum 10 of the hammer causes it to continue this motion independently against the resistance of small spring h', and thus strike a cushioned or graduated blow instead of a violent one. The spring G simultaneously returns the trip-bar E to its original position. The spring h' 15 does the like for the hammer, and the slide-plate C falls by its own weight when released and closes opening b.

Having thus described my invention, what I 20 claim as new, and desire to secure by Letters Patent, is—

1. In combination with a letter-box, a slide-plate which closes and opens the opening for letters and is provided with a rigid rearwardly-extending arm, a trip-bar engaged by 25 said arm, a hammer arranged to be drawn back by said trip-bar, and a spring for operating said hammer and replacing said trip-bar, substantially as set forth.

2. A hammer, a pivoted carriage on which it is pivoted, and a spring, h', between said hammer and carriage, in combination with a trip-bar having a nose which engages a nose 30 on said hammer-carriage, a spring, G, engaging said carriage and trip-bar, and a slide-plate 35 operating said trip-bar to turn the hammer-carriage against the action of the spring G, substantially as set forth.

3. In combination with alarm mechanism and a letter-box inclosing the same and having in its front a vertical slot and also a passage for letters, a front plate recessed on its inner face and provided with opening a, and a vertical slot communicating therewith, and a slide-plate which moves up and down in 45 said recess to open and close opening b, said slide-plate being provided with a handle which extends forward through the vertical opening in said front plate, and an arm extending rearwardly through the vertical slot in the front 50 of the box to engage with the alarm mechanism and operate it, for the purpose set forth.

4. The pivoted hammer-carriage F, constructed with a nose, f, and a tongue, f', in combination with a trip-bar having a nose 55 which engages and releases, as described, the nose aforesaid, a fixed lug which guides said noses and also limits the play of said hammer-carriage, a slide-plate arranged to raise the trip-bar for turning the hammer-carriage 60 when said slide-plate is lifted, a hammer pivoted on said hammer-carriage to continue the stroke by momentum when the motion of said hammer-carriage ceases, and a spring in contact with said hammer which resists this in- 65 dependent motion of the latter and replaces it in its former position, substantially as set forth.

In testimony whereof I affix my signature in presence of two witnesses.

FREDERICK SNYDER.
